nois

Application April 11, 1941, Serial No. 388,038

12 Claims. (Cl. 274—13)

The present invention is concerned with a simple and dependable record cutting mechanism which, as a self-contained unit, is adaptable to certain existing phonographs for the purpose of cutting sound grooves in a disk record whose surface is suitably prepared for this operation. Such a device is particularly adapted for home use, and in its operations no complications or special manipulations need be involved.

The present improvements are directed to such a unitary mechanism having special provision against back lash arising from play or slack in the transmission; and having a dependable frictional drive in the transmission by which power is supplied to slowly advance the arm whereon the cutter is mounted.

These and other features as will hereinafter appear may be embodied in certain mechanisms of which two exemplifications are set forth in the accompanying drawings in the manner following:

Figure 1, which is a top plan view of a phonograph base illustrates a record with cutting mechanism in place, also a tone arm which is swung out of the way to one side;

Fig. 2 is an enlarged detail in section taken on line 2—2 of Fig. 1;

Fig. 3 is a detail in perspective showing the under side of the cutter and the adjustable spring therefor;

Fig. 4 is a fragmentary bottom plan view showing the under side of the phonograph base and motor thereon, together with one form of transmission for driving the turntable and the cutter mechanism;

Fig. 5 is an enlarged detail in vertical section taken on line 5—5 of Fig. 4;

Fig. 6 is a sectional detail of another form of transmission which may be incorporated into the general assembly shown in Fig. 4; and

Fig. 7 is a view in section, taken on line 7—7 of Fig. 6.

Referring to Fig. 1, we have shown a conventional phonograph base B in the form of a platform adapted to be mounted within or upon an appropriate cabinet, portable or otherwise. Extending through the base is a spindle 10 adapted to be received within the central opening of a turntable T, and, according to the drive that is shown by way of example, this spindle is in frictional engagement with the turntable to establish a driving connection therefor. Upon the turntable a disk record R is adapted to be rested with its central opening receiving the spindle whereby to maintain a concentric relationship therewith.

5 A cutter arm A is swingingly mounted at one side of the base, preferably near one corner, in such a position as to rest, when inactive, within a yoke bracket 11, and to extend over a record to produce sound grooves therein when in the position shown in full lines in Fig. 1. A tone arm 12 is also swingingly mounted upon the base, being equipped, if desired, with an electric pickup 13 for tracking in the grooves of a record when swung from an inactive position (as shown) to the usual playing position (not shown).

10 Any suitable driving mechanism may be employed to rotate the turntable. As shown, a center type of drive may be used, comprising an open frame F supported by and depending from the base to expose certain meshing gears including a spur gear 15. The motor may include a stator (field) 16 and a rotor (armature, not shown) 17 from which is extended a shaft that enters into a housing 18 wherein is accommodated certain reduction gearing, including a driven shaft 19 which extends vertically to support and drive the spur gear 15. The motor as well as the housing 20 for the reduction gear all are supported by the base as by means of a horizontal plate frame 19 connected as by screws 20 with certain posts which depend from the base.

15 The mechanism described up to this point is entirely conventional and forms no part of our invention. We propose to utilize, however, any of the existing drive mechanisms available for our purpose for the operative attachment thereto of the cutter mechanism which will now be explained in detail.

20 Through the base plate, preferably at one corner as already suggested, is an opening for receiving an elongated vertical bearing 25 adapted to extend partly above and partly below the base to which the bearing may be secured conveniently as with the aid of a nut 26. This bearing accommodates a post 27 which has capacity for turning movement therein, the upper end of the post carrying a head 28 which is locked fast thereto and provided with a hinge connection at 29 for the support of the arm A. Pressure exerted radially of the hinge connection, as by a spring 29a, will serve to prevent any play or loose movement at this point. An adjusting screw 30, 25 which may be secured with the aid of a lock nut 31 in a desired position of adjustment within the head 28, provides a stop for limiting the downward swinging movement of the arm A. In normal practice, this adjustment is such as to permit the arm to descend to a desired point.

A shield 35 of generally conical form may be fitted around the upper end of the bearing, so as to present an ornamental and attractive appearance where it would otherwise be exposed above the base plate. Below the base the bearing is joined to a bracket 36 which extends laterally toward the turntable drive (here shown as near the center of the base), the bracket being provided with a pair of depending ears 37 and 38 formed with aligned bores therethrough so as to furnish bearings for a shaft 39. One end of this shaft, which is positioned relatively close to the turntable drive, carries a worm wheel 40 in mesh with a worm 41 on a shaft 42 whereon is mounted fast a gear 43 that may be placed in mesh with the spur gear 15 through one of the openings in the frame F. The bracket is fixed in position by its connection with the bearing 25 at one end and elsewhere as by a screw 45 which passes through the base for threaded connection with a boss 46 upstanding from the bracket at a point relatively remote from its fixed end. In this way motion originating with the motor is assured of transmission through the shaft 39 to its end adjacent the bearing where it carries a worm 47 in mesh with a worm gear 48 having a free mounting upon the lower end of the post 27 where it is of reduced diameter, as best shown in Fig. 5.

Our invention is concerned largely with the driving connection that is established between the worm wheel 48 and the post 27 so as to provide an even and assured flow of power free of back lash under all operating conditions. For this purpose, we have shown two forms of transmission of which one, illustrated in Figs. 4 and 5, will first be considered.

Around the reduced lower end of the post is fitted a friction plate 50, desirably of steel, brass, bronze, fibre or other suitable material, the plate being formed with a tongue 51 upstanding from its periphery at one point in a position which permits engagement successively with opposite sides of the bracket 36 if the arm A be swung to its limit in either direction. This plate is locked to the post 27 in any convenient manner, as, for example, by swaging the post at 52. In its peripheral region the plate may be offset to provide an annular bearing surface 53 which is adapted to engage a friction disk 54 having a relatively greater coefficient of friction, such as Bakelite or the like. By reason of the peripheral offset of the plate, its frictional contact with the disk is confined to the annular offset area near the periphery of the plate. The disk is also in engagement with one face of the worm gear 48 to which it may be secured non-rotatably as by a pin 55.

The opposite face of the gear is engaged by a brake disk 56 having a relatively greater coefficient of friction, cork, Bakelite or other suitable material being suggested for its composition. This brake disk 56 is desirably larger in diameter than is the friction disk 54. Because of this relationship, the larger brake disk provides a greater area of friction surface than is afforded by the smaller friction disk 54. The frictional properties of the larger brake disk are also relatively greater than those of the smaller friction disk, and the friction surface is located at a greater radial distance from the center of movement, so that there is an overbalancing of frictional resistance on the side of the worm gear which is engaged by the larger brake disk 56.

In engagement with the brake disk 56 is an an-

nular engaging surface offset from another friction plate in the form of a washer 57, desirably made of or faced with steel, brass, bronze, or other suitable material, and against this washer pressure may be exerted by a coil spring 58 which surrounds the post. The spring may be secured in place as by a washer 59 which is adjustably supported on the lower threaded end of the post with the aid of a pair of lock nuts 60.

One of the several elements contained in the assembly just described, preferably the friction plate 50, is locked to the post 27, the remaining plates and disks being free. The friction plate 57 is provided with an extension arm 61 which leads to a boss 62 depending from the base plate so as to receive therein a screw 63 which traverses the arm to secure the latter in fixed relationship to the base. In this way the plate 57 is held fixedly against motion.

The cutter arm A which is swingingly mounted upon a post upstanding from the base plate, is desirably channeled upon its under side to accommodate a cartridge H which contains the motivating element for a cutting tool 65. At the end of the cartridge opposite the tool is a pair of spaced pointed lugs 66 adapted to be fulcrumed within aligned angular crotches of a plate 67 which is secured within the cutter arm (see Fig. 3). The cartridge is accordingly free to rock through a vertical plane about the crotches as an axis. The cartridge which is relatively heavy will tend to swing down at its free end where the tool is positioned, and to control the gravity force which causes the tool to engage the record to produce sound grooves therein there is provided a ledge 68 extending rearwardly from the cartridge at a point just above the crotch (see Figs. 2 and 3); one end of a coil spring 69 is connected to the ledge, its opposite end 70, which is bent in the form of an eye, being fitted around the threaded shank 71 of a screw having a knurled head 72. One end of the shank 73, which is pointed, is journalled within a bearing 74 depending from the arm A, the opposite end being journalled within a bearing 76 that is provided in a cross plate 76 which extends transversely of the arm. Wiring connections 77 extend through the arm into the cartridge to transmit electrically thereto the sound vibrations that are to determine the character of the grooves produced in the record by the cutting tool 65.

By rotating the knurled head 72 which is accessible upon the under side of the arm the position of the spring eye 70 may be shifted vertically. The screw shank 71 is obliquely disposed whereby the spring is placed under greater tension when the eye is moved in a downward direction; its tension is decreased when the eye is advanced in the opposite direction. By adjustments of the screw the tension on the ledge 68 may be varied, thereby affecting the counter-force of the spring 69 which acts upon the cartridge to control the pressure with which the tool is tracked in the record.

In Figs. 6 and 7 we have shown a modified brake mechanism which will now be described. Insofar as the parts illustrated in Figs. 6 and 7 are the same as those shown and described in connection with Fig. 5, they carry corresponding reference numerals.

The post 27 which extends through the bearing 25 is provided with a friction plate 80 connected fast thereto and formed adjacent its periphery with a lug 81 to which is connected one end 82

of a tension spring 83 whose opposite end 84 is fastened to a screw 85 which takes into a boss 86 depending from the bracket 36. The friction plate 80 is engaged on its under surface by a friction disk 90 against which bears one face of a worm gear 48 which receives thrust pressure from a coil spring 91 encircling the post and adjustably tensioned as by a nut 60 which is screw-threaded on the reduced lower end of the post. The friction plate 80 is subject always to the tension force exerted by the spring 83 which, as best shown in Fig. 7, is extended around the bearing 25 so as to apply effectively a torsion force tending to prevent movement of this plate 80 together with the post connected thereto.

When the cutting tool engages with a record, several forces are set in motion which produce a condition that is dealt with very effectively by the mechanism of this invention. With the record rotating in the direction indicated by the arrow in Fig. 1, the force that is required for the tool to plow a groove in the record is exerted on the cutting arm A in the direction shown by the arrow along the line *a* which is tangent to the radius of the cut. This force operates on a moment arm indicated by the line *b* tending to swing the cutting arm toward the center of the record. This swinging movement becomes less as the tool draws nearer to the center of the record until, at the end of the cut, with the needle at *c*, the moment arm is of the length shown by the line *d*. This force, however, assures maintenance of a firm contact between the one set of interengageable faces of the teeth on the worm wheel 47 and worm gear 48.

With the mechanism shown in Figs. 6 and 7, the spring 83 exerts a torque on the shaft in the same direction, tending to make more intimate the contact between the interengaging faces of the teeth already referred to. There is also at times a further force produced by the cut grooves in the record occasionally tangling and reacting on the cutting tool with the result that there is a tendency to pull the arm A toward the center. When several threads are thus tangled, this force may become considerable. With the spring mechanism shown in Figs. 6 and 7, any such force simply combines with the other forces already noted to make the facial contact between the teeth of the worm wheel and worm gear more intimate.

With the springless type of drive shown in Fig. 5, there is at all times a brake friction which retards the floating worm gear 48. This compels the worm wheel 47 to pull this gear so as to increase the intimacy of contact between one set of the faces of the interengaging teeth on the worm wheel and worm gear. To this is added the force resulting from plowing of the groove in the record, also any torsion force tending to pull the cutting arm A toward the center, so that the value of the braking effect of the smaller friction disk 54 should desirably be high enough to prevent these combined forces, resulting from plowing of the groove and inward swinging of the cutting arm, from setting up any back-lash from the interengaging teeth. This high value of brake effect which is afforded by the mechanism under discussion is added to the motor load at a time when the cutting tool is in action.

It is always desirable to play back a record at approximately the same speed as it was turning at the time the sound grooves were formed therein. With the springless brake device of Fig. 5, there is applied to the motor one heavy friction

load which continues while the record is being cut. On the play-back, however, another friction, i. e., that which obtains between the smaller friction disk 54 and the worm gear 48, is added to the motor load, but this is less than is the friction obtaining between the larger brake disk 56 and the same worm gear. It follows, therefore, that the amount of extra load put on the motor, by the friction developed through engagement of the smaller friction disk 54 with the worm gear 48, will not compensate for the reduction in motor speed which will take place when the groove is being cut in the record.

The spring type of mechanism (Figs. 6 and 7) eliminates brake friction while cutting of the record proceeds, and the only load on the motor is that which is produced by the cutting needle plowing the groove. On the play-back, however, the cutting arm A is usually set back out of the way upon the bracket 11, so that the friction disk 90 automatically becomes a brake the value of which can be so adjusted, by manipulation of the nut 60, as to impose on the motor a load which is approximately equal to the load of the cutting tool. It is manifest, therefore, that by the means herein disclosed we have provided effectively for elimination of play or back-lash—an important consideration because of imperfect reproduction of sound which would otherwise result.

We claim:

1. In a phonograph having a rotatable post adapted to carry a cutter arm, a power transmission in connection with the post comprising a friction plate in fast connection therewith, a second friction plate having a loose mounting on the post, a fixed connection for the second plate, a pair of friction disks loosely mounted on the post, one engaged by each plate, and a gear wheel loosely mounted on the post receiving engagement from the two disks whereby rotation is imparted from the gear wheel to one disk and thence to the plate in fast connection with the post and a brake action is imparted by the other plate acting through the other disk, thence through the gear wheel, the remaining disk, and through the plate in fast connection with the post.

2. In a phonograph having a rotatable post adapted to carry a cutter arm, a power transmission in connection with the post including a gear wheel and a plurality of interengaging disks and plates assembled operatively therewith, one of the plates having a fast connection with the post, a fixed connection for another plate, and spring means exerting pressure axially of the assembly of plates, disks and gear wheel whereby to enhance the frictional connection therebetween.

3. In a phonograph having a rotatable post adapted to carry a cutter arm, a power transmission in connection with the post including a pair of plates mounted on the post, one in fast connection therewith and the other loose thereon, a fixed connection for the loose plate, a gear wheel loosely mounted on the post between the plates, spring means urging the loose plate toward the gear wheel and the gear wheel toward the fast plate whereby to establish a frictional drive between the gear wheel and the fast plate, and means for positively driving the gear wheel whereby to transmit therefrom through the fast plate a friction drive to the post while receiving from the loose plate a sustained braking action to prevent back lash.

4. In a phonograph having a rotatable post

adapted to carry a cutter arm, a power transmission in connection with the post including two sets of friction elements mounted on the post, all but one of the elements being loose with respect to the post, means establishing a fast connection between the remaining element and the post, a fixed connection for one of the remaining elements, a gear wheel loosely mounted on the post between the two sets of elements, spring means urging the loose elements and gear wheel axially toward the fast element, and means for positively driving the gear wheel whereby to transmit therefrom through one set of elements, including the one which is fast on the post, a friction drive to rotate the post while receiving from the loose element which is fixed a sustained braking action to prevent back lash.

5. In a phonograph having a base and a rotatable post adapted to carry a cutter arm, a transmission including a disk mounted on the post and locked thereto, a gear wheel mounted to rotate freely on the post and engaged on one side by the disk, a second disk engaging the opposite gear wheel side mounted freely on the post and having an anchorage with respect to the base, and spring means exerting a thrust axially of the post upon the disk-gear wheel-disk assembly thereon for maintaining a substantial friction therebetween whereby a driving force imparted to the gear wheel will be transmitted through the locked disk to turn the post.

6. In a phonograph having a rotatable post and a motor, a transmission for establishing a driving connection between the motor and the post comprising a gear wheel freely mounted on the post, a pair of friction disks in engagement with opposite faces of the gear, a pair of friction plates in engagement with the disks, means establishing a fast connection between one of the plates and the post, and means connecting the other plate fixedly with the base whereby the gear which is frictionally engaged by the adjacent disks will serve to transmit therethrough rotary motion to the post free of back lash.

7. In a phonograph having a base, a rotatable post and, a gear wheel freely mounted on the post, a power transmission in connection with the gear wheel, a friction drive between the gear wheel and post, a pair of friction disks freely mounted on the post one on each side of the gear wheel in engagement therewith, means establishing a fast connection between one disk and the gear wheel, a pair of friction plates, one in engagement with each disk, means establishing a fast connection between one plate and the post, and means establishing a fixed connection between the other plate and the base, whereby when rotation is imparted to the gear wheel, a friction drive is established to the post through the medium of one friction disk and the plate adjacent thereto and a braking action is imparted to the post through the medium of the other plate in cooperation with the remaining disk.

8. In a phonograph having a base and a ro-

tatable post, a power transmission in connection with the post including a gear wheel and a plurality of interengaging friction plates and disks assembled operatively therewith, the disks having engagement with opposite faces of the gear wheel and the plates having peripheral offsets to define annular surfaces of relatively small area in engagement with the associated disks, one of the plates, of lesser diameter than the other, being secured fast to the post and the remaining plate of larger diameter being secured fast to the base, and spring means exerting pressure axially of the assembly of plates, disks, and gear wheel, whereby to enhance the frictional connection therebetween.

9. In a phonograph having a base and a rotatable post, a power transmission in connection with the post including a gear wheel and a plurality of interengaging disks and plates assembled operatively therewith, means connecting one of the disks with the gear wheel, means connecting the plate adjacent the last named disk with the post, means connecting the other plate with the base, the engaging surface of the plate connected to the post being of less area and at a lesser radial distance than the engaging surface of the other plate, and means exerting a thrust pressure upon the gear wheel-disk-plate assembly to enhance the frictional connection therebetween.

10. In a phonograph having a base and a rotatable post, a power transmission in connection with the post including an assembly of friction elements and a gear wheel mounted on the post, one of the elements of maximum friction value being anchored fixedly relative to the base and another of lesser friction value being connected fast to the post, and means acting to maintain the wheel-friction-element assembly in frictional driving relation.

11. In a phonograph having a base and a rotatable post, a power transmission in connection with the post including a gear wheel having a free mounting thereon, a friction plate mounted on the post and fast thereto, a friction disk freely mounted on the post between the plate and gear wheel and in engagement with each, means acting to maintain the plate-wheel-disk assembly in frictional driving relation, and spring means exerting a torsional force against the friction plate and post connected therewith in opposition to a power force transmitted thereto through the gear wheel.

12. In a phonograph having a base and a rotatable post, a power transmission in connection with the post including a gear wheel having a free mounting thereon, and a friction element connected fast with the post and in engagement with the gear wheel, means for maintaining the friction element and gear wheel in driving relation, and means applying to the friction element a torsion force in opposition to the driving force transmitted thereto by the gear wheel.
